(57) CLAIM

The ornamental design for an exfoliating disc head, as shown and described.

DESCRIPTION

FIG. 1 is a perspective view of an exfoliating disc head suitable in accordance with our new design, the exfoliating disc head suitable for use with a personal care appliance;

FIG. 2 is a top view of the exfoliating disc head of FIG. 1; FIG. 3 is a front view of the exfoliating disc head of FIG. 1; FIG. 4 is a rear view of the exfoliating disc head of FIG. 1; FIG. 5 is a left side view of the exfoliating disc head of FIG. 1; and,

FIG. 6 is a right side view of the exfoliating disc head of FIG. 1.

The broken lines immediately adjacent the shaded areas represent the bounds of the claimed design while all other broken lines are directed to environment and are for illustrative purposes only; the broken lines form no part of the claimed design.
